UNITED STATES PATENT OFFICE

ELMO E. SMITH AND KARL L. BUNZE, OF CHICAGO, ILLINOIS

DESIGN FOR A COMBINED LIGHTER AND TOBACCO CONTAINER OR THE LIKE

Application filed November 7, 1932. Serial No. 45,807. Term of patent 7 years.

To all whom it may concern:

Be it known that we, ELMO E. SMITH and KARL L. BUNZE, citizens of the United States, residing at Chicago, in the county of Cook and State of Illinois, have invented a new, original, and ornamental Design for a Combined Lighter and Tobacco Container or the like, of which the following is a specification, reference being had to the accompanying drawing, forming part thereof:

The drawing is a perspective view of our improved combined lighter and tobacco container.

We claim:

The ornamental design for a combined lighter and tobacco container, or the like, substantially as shown.

ELMO E. SMITH.
KARL L. BUNZE.
